UNITED STATES PATENT OFFICE.

JOHN H. HUTCHINSON, OF PORT MELBOURNE, VICTORIA, AUSTRALIA.

CONTROLLING MEANS FOR DUMPING BODIES.

Application filed March 19, 1923. Serial No. 626,193.

To all whom it may concern:

Be it known that I, JOHN H. HUTCHINSON, a subject of the King of Great Britain, residing at Port Melbourne, Victoria, Australia, have invented certain new and useful Improvements in Controlling Means for Dumping Bodies, of which the following is a specification.

This invention relates to improvements 10 in controlling means for dumping bodies on motor vehicles or the like.

Among the objects of the invention is to provide improved devices employed in connection with load-carrying bodies of the 15 above character which will enable the same to be brought to dumping position quickly and easily; and which will enable the same to be returned to normal position and locked 20 against movement in a positive and reliable manner.

It is also an important object of the invention that the devices employed for controlling and movably supporting bodies of this character be adapted to be applied to 25 any conventional type of vehicle.

Other objects, and objects relating to details of construction, combination and arrangement of parts will hereinafter appear in the detailed description to follow.

30 The invention is illustrated by way of example in the accompanying drawings, in which:

Figures 1 to 6, inclusive, are similar detail views illustrating different ways of 35 movably supporting "dump" bodies,

Figure 7 is a view in end elevation illustrating an improved means of this invention for locking a dump body which is movable transversely of the supporting vehicle 40 therefor,

Figure 8 is a view in rear end elevation showing a body locking and releasing means of the present invention, said body being movable longitudinally of the supporting vehicle,

Figure 9 is a detail view showing form of shackle employed in arrangement shown in Figure 7,

Figure 10 is a vertical longitudinal sectional view with parts broken away of a 50 movable "dump" body and rails therefor, and illustrating the locking and releasing means shown in Figure 8 and also means for

tipping the body to bring the same to its dumping position,

Figure 11 is a detail view showing form of tipping rod employed,

Figures 12 and 13 are end elevations showing means for supporting rails upon which a dump body may move,

Figure 14 is a detail view in rear elevation showing means for controlling tipping movement of a dump body and also for returning the same to its original position, and

Figure 15 is a view in side elevation showing a motor vehicle with a "dump" body together with controlling means shown in Figures 12 to 14, inclusive.

Like reference characters designate corresponding parts throughout the several views of the drawings.

Referring to the drawings more particularly, in Figures 1 to 6, A indicates generally the bed or bottom of a movable "dump" body. In Fig. 1 this body carries pieces of 75 studding B one adjacent each longitudinal edge. Each studding carries a plurality of rollers E, each roller being journaled by a pin D which is supported by a pair of bracket members C. In Fig. 2 the rollers E 80 are preferably grooved as shown and the supporting means for each roller comprises a U-shaped bracket as shown. In Figure 3 the rollers F are carried by a shaft D¹ and said shaft being journaled by bearing members C¹ carried by the studs B. In Figure 4 the rollers E² are arranged in pairs and each pair journaled by a suitable bearing C² carried upon the bottom face of bed A. In Figure 5 channel rails G are provided which 85 rotatably support rollers E⁴ adapted to movably support bed or body A, and in Figure 6 rollers E⁵ are formed to co-operate with inverted channel members H to movably support the body or bed A.

In Figure 7 the body supporting side member A⁴ is movably supported by rollers upon rails carried by a motor vehicle or the like and these rails extend transversely of the motor vehicle. In order to lock the body in its receiving position, I provide the two link members J each comprising two bars as shown in Figure 9 which are connected at a point intermediate their ends, as at K, and each link has one end M pivotally connected to the body A and its remaining end L simi-

larly connected to the associated rail by a pin N, said pin N being preferably secured by a chain as shown. In utilizing this arrangement the links J when connected as shown prevent movement of the body and the body can be easily released by removal of pins N.

In Figure 8 there is shown two castings O, each of which is of the shape best shown in Fig. 10. The casting may be secured at the forward end of a vehicle upon which a body is longitudinally movable; and each casting is formed with a longitudinally extending passageway P adapted to receive the depending flange O² of a body supporting side member O³, Fig. 10.

Each casting O is formed with an upstanding projection X which forms a stop for limiting forward movement of the associated dump body and also provides a fulcrum for a bar in starting the dump body rearwardly upon the associated vehicle. Each casting carries a locking pin Q which may be shifted longitudinally by a lever R. Each pin Q is adapted to move into the associated passageway P, transversely thereof, and enter opening O⁴ in the end of the associated body supporting member O² and thereby lock the body against movement. Each lever R is fulcrumed as shown in Figure 8, and its one end suitably connected as at S to a rod T whereby said pins Q may be shifted from locking position. The rod T carries a collar V and between this collar and a casting O there is interposed a compression spring U whereby to hold the pins Q in locking position. Also each casting O carries an elongated plate member W which is pivotally supported for swinging movement as shown in Figure 10 and which is drawn by spring W¹ to move into the path of the associated pin Q. Upon the rod T being operated to move the pins Q for releasing the dump body the member W will move into position to prevent return movement of pins Q, and thus upon the members O² being returned into passageways P with force the members W will be engaged and moved to permit the pins Q to assume their locking positions with relation to the associated dump body. In Figure 10 it will be observed that wheels or rollers E¹ movably support the dump body supports O² upon rails B¹. Between the rear ends of these rails there is secured a plate A² which carries a hook member A¹ positioned centrally with respect to the ends of the plate. Also the plate A² may rest upon the supporting plate B² of the associated vehicle. In Figure 11 there is shown in section a frame member of a dump body which is arranged longitudinally of the body and carries a pair of prongs C² which support therebetween a pin D¹. The member C² should be pivotally attached to the frame members of dump

body, as indicated in Figure 10. With the rearward movement of the dump body the pin D¹ carried thereby will engage the hook A¹ and tip the body so that the same may assume its dumping position.

In Figure 15 there is shown a motor vehicle, and upon the chassis frame of the same there is supported a pair of rails G¹ by brackets H¹. The bracket members may be of the form shown in Figure 12 or of the form shown in Figure 13. Re-inforcing members L¹ may be employed and these members, together with the brackets, may be secured to the chassis frame by bolts K¹. Channel rails G¹ may be employed upon which the body may be movably supported as illustrated. The forward end of the dump body may have connected thereto the one end of a cable R¹ and the other end of the cable secured to a drum M¹. The shaft carrying drum M¹ may have associated therewith a ratchet wheel U¹ and pawl T¹, and also a bracket member O¹ for turnably supporting, in conjunction with rails G¹ a shaft N¹, said shaft N¹ carrying a pinion in mesh with a cog wheel carried by shaft carrying drum M¹. The shaft N¹ may be provided with a crank as shown for manually rotating and thereby controlling movement of associated dump body. Also the shaft N¹ may carry a brake drum P¹ which may have a brake band operatively associated therewith and the lug Q¹ formed upon the bracket O¹ employed for securing the brake band in an obvious manner.

As is obvious from Figure 15 the drum M¹ and associated operating means may be employed for returning the dump body to its normal position after the same has been tipped to its dumping position.

A tail gate 5 may be employed for the dump body and this gate may have connected thereto the one end of a cable 4 which may be controlled by a suitable drum 2 and hand lever 3. Also a prop S¹ may be provided which has its one end pivotally secured to one of the rails G¹ and its other end adapted to be brought to engage the dump body as shown.

I also find it desirable to employ a jack V¹ which is hinged to the rear end of the motor vehicle chassis as shown and adapted to be swung to a vertical and operative position. The jack has its base W² preferably rounded, and one end of a cable X¹ is connected to the lower end of the jack. The other end of this cable is secured to an eye Y¹ and this may be engaged with a hook Z¹ and thereby to hold the jack V¹ in its non-operative position. Also ramps 6 may be employed for elevating the forward end of the vehicle and these ramps when not in use may be suspended in any convenient manner for the vehicle, as indicated at 7.

It is thought from the foregoing descrip-

tion, taken in connection with the drawings referred to, that the construction and operation of the different controlling devices of this invention may be clearly understood.

5 It has been found that these devices can be used in a highly efficient manner to advantage in controlling a dump body when it is desired to discharge the load therefrom.

It also should be pointed out that the 10 dump body of vehicle supported as shown and described herein could be entirely removed from the supporting tracks of the vehicle and moved upon other tracks provided therefor. In this way the body of the 15 vehicle could be moved to a place for unloading in an easy manner.

Having now particularly described and ascertained the nature of my said invention and in what manner the same is to be per-

20 formed, I declare that what I claim is:—

1. In combination, a movable body having a pair of protrusions at one end, a pair of locking members one for each protrusion and each locking member having a socket 25 adapted to receive the associated protrusion and associated locking member having transverse openings adapted to be brought into registering relation, spring pressed pins adapted to enter said openings and thereby 30 lock the movable body against movement, and combined rod and lever means whereby to simultaneously move said pins to a releasing position with respect to said protrusions.

35 2. In combination, a movable body having a protrusion at one end, a locking member having a socket for receiving said protrusion, said protrusion and locking member having transverse openings adapted to be brought into register, a spring pressed member adapted to be normally disposed in register with the openings in said locking member and be moved from this position by pressure from said protrusion upon the movable body, and a locking pin adapted to be inserted in the openings of the locking member and opening in the protrusion of the 45 movable body when said openings are brought into register.

50 3. In an apparatus of the character de-

scribed, a pair of rails, a wheel-supported body movable upon said rails, a plate extending between said rails and disposed therebeneath, means for securing the plate to said rails, a hook formed upon the plate 55 at a point central to the length thereof and upon the upper face of said plate, and means carried by the movable body adapted to engage with said hook.

4. In combination, a removable body having a protrusion at one end, a locking member having a socket for receiving said protrusion, said protrusion and locking member having transverse openings adapted to be brought into register, a yieldable member 60 adapted to be normally disposed in register with the openings in said locking member and also adapted to move from this position by pressure from said protrusion upon the movable body, and a locking pin adapted 65 to be inserted in the openings of the locking member and opening in the protrusion or movable body when said openings are brought into register.

5. In combination, a vehicle, a jack having its one end pivotally connected to the end of said vehicle and adapted to be swung into position for supporting the associated end of the vehicle, and a rounded ground-engaging member carried by said jack and 70 adapted to facilitate the movement of said jack into its operative position with respect to said vehicle.

6. In combination, a vehicle chassis, rails supported thereby, a body movable upon the rails, an upstanding casting at the inner end of said rails with relation to the movement of the body, said casting having a slot in the forward face thereof, a protrusion carried by the vehicle body adapted to enter said 85 slot when the vehicle body is brought into proper position with respect to the casting, and means adapted to automatically engage the protrusion carried by said body when within the slot of the casting and lock the 90 body against movement.

Dated this nineteenth day of February, 1923.

JOHN H. HUTCHINSON.
